UNITED STATES PATENT OFFICE.

NEWTON CRANE, OF BOSTON, MASSACHUSETTS, ASSIGNOR, BY DIRECT AND MESNE ASSIGNMENTS, TO CHARLES F. BROWN, OF READING, MASSACHUSETTS.

ELECTRICAL SAFETY-RAZOR.

1,303,539.

Specification of Letters Patent. Patented May 13, 1919.

Application filed July 19, 1907, Serial No. 384,507. Renewed August 11, 1917. Serial No. 185,799.

To all whom it may concern:

Be it known that I, NEWTON CRANE, of Boston, in the county of Suffolk and State of Massachusetts, have invented certain new and useful Improvements in Electrical Safety-Razors, of which the following is a specification.

This invention has relation to an apparatus for shaving. It has heretofore been proposed to construct a safety razor with a reciprocating blade having a smooth edge, and with an electromagnetic mechanism for effecting the reciprocation of the blade. The electromagnetic mechanism comprised two electromagnets adapted to alternately attract the ends of the centrally pivoted armature connected to the blade, there being suitable make-and-break mechanism for closing the circuits alternately through the electromagnets. So far as I am aware, a device of this character has not been in practical use, owing to the character of the mechanism suggested for the purpose of reciprocating the blade.

The object of the present invention is manifold. One of its objects is to provide for a safety razor having a reciprocatory smooth-edged blade, and a rotary motor for effecting the reciprocation of said blade without causing a disagreeable vibration of the safety razor itself. In accomplishing this object of the invention, I have had further in mind to provide a light motor of such compactness that it could be mounted in the handle of the razor, and of such power that it could effect the reciprocation of the blade with the proper force and energy and at a high rate of speed. By employing a rotary motor, the only reciprocating part is the blade itself which, being light and vibrated at high speed, is insufficient to overcome the inertia of the razor as a whole, so that the razor may be used with the same facility as one in which a stationary blade is mounted. A further object of the invention is to so construct the razor that the blade-carrying end may be immersed in water without danger of moisture finding its way to the motor itself.

Figure 1 represents a longitudinal section through the razor on a plane parallel with the edge of the blade.

Fig. 2 represents a section on the line 8—8 of Fig. 1.

Fig. 3 represents a section on the line 9—9 of Fig. 2.

Fig. 4 represents a section on the line 10—10 of Fig. 2.

Fig. 5 represents a section on the line 11—11 of Fig. 2.

Figs. 6, 7 and 8 respectively represent the connection between the armature shaft of the motor and the blade.

Fig. 9 represents the head of the razor.

Fig. 10 represents an edge view thereof.

Fig. 11 represents a section therethrough.

Fig. 12 represents an end view thereof.

Fig. 13 shows the head of the razor with the pivoted plate raised and with the blade removed.

Fig. 14 illustrates the blade.

Fig. 15 illustrates one of the blade adjusting disks.

The form of razor embodying my invention herein illustrated consists of a tubular handle 44, one end of which is closed by a cap 71 having an aperture through which the cable extends. An insulated bushing 72 is inserted in the aperture as shown. The other end of the handle is internally threaded as at 73, to receive a holder, comprising an external threaded support 74, a plate 75 and a hinged cover plate 77. To said support 74 is secured by any desired means the plate 75 which is adapted to receive and guide the blade 76. The said plate 75 is substantially rectangular in plan view, as shown in Fig. 13, and is formed with the usual teeth 177 which bear against the face of the person shaving. The plate 75 is recessed or rabbeted to receive the blade 76, said blade being held in place by a cover plate 77 hinged to the plate 75, as shown in Figs. 11, 12 and 13. The blade 76 is illustrated in Fig. 14. It has a smooth cutting edge and at its ends is provided with slots 78 to receive guide pins 79 which hold it against all except longitudinal movement. These guide pins, as shown in Figs. 11, 13 and 15, are formed eccentrically upon disks 80 arranged in apertures in the plate 75 near the ends thereof. Each disk has in its outer end a slot 81 to receive an instrument by which it may be rotated, and is also formed with a peripheral or circumferential groove 82 to receive the end of a set screw 83 passed into the end of the plate 75, as shown in Fig. 1. By loosening the set screws 83 and

rotating the disks or adjusting members 82, the blade 76 may be adjusted transversely of its longitudinal path of movement. The hinged cover plate 77 is held in its operative 5 position by clamping members 84—84 pivoted to the under side of the plate 75, as shown in Figs. 9, 12 and 13. Each clamping member has a fin or web 184, see Figs. 9 and 13 adapted to enter an aperture 85 in the 10 end of the plate 77 as shown in dotted lines in Fig. 12. An important feature of the invention is the construction of the holder which adapts the blade to free itself of bits 15 of hair or other matter which might work between the members of the holder and the blade. As appears from the drawings, the plates 75 and 77 which embrace the blade bear on the opposite surfaces thereof adjacent the cutting edge of the blade, and form 20 a runway or guideway in which the blade is held. As appears from Figs. 2, 11 and 12, the bearing of the plates is not continuous over the entire surface of the blade, but that bearing near the cutting edge of the blade 25 is only near the outer edges of the plates. A short distance back of the edges of the plates and blades, the plates are cut away, leaving shoulders 751 and 771 respectively, back of which are clearance spaces on both sides of 30 the blade. These spaces are provided in order that the bits of matter which work into the guideway may be freed from the bearing surfaces of the blade and plates, so that they will not cause the blade to stick. 35 Arranged in the handle of the razor is a rotary motor. This motor may be made in any suitable way. I have illustrated the field magnet 90 as being of the permanent type with the two opposing poles 91, 91 which extend toward the cap end of the 40 handle. The neutral end of the magnet is arranged close to an internal flange 92, between which and the magnet is inserted a waterproof packing 93. The magnet is held 45 in place by screws 94 as shown in Fig. 2. Through the neutral end of the magnet and through the washer and flange 92, is a sleeve 95 having at its ends bushings 96 which are preferably made of graphite or other suitable 50 material. To the ends of the poles of the magnet is secured a metallic or soft iron brush-supporting member 97. This consists of a disk having a flange 98 to overlap the ends of the pole pieces of the magnet 55 and a hub 99 to receive a bushing 100 formed of any suitable material, such as graphite. The three bushings 96, 96 and 100 are arranged in axial alinement to receive the armature shaft 101 which is journaled 60 therein. The upper end of this shaft projects through the bushing 96 and is threaded to receive a crank member 102. Said crank member 102 has an eccentric threaded aperture to receive an eccentric or crank pin 103 65 which extends through an aperture in the plate 75, and enters a slot 105 in the rear edge of the blade 76. When the armature shaft is rotated, the crank member and crank pin effect the reciprocation of the blade. The longitudinal movement of the 70 blade need not exceed one-thirty-second to one-sixteenth of an inch. Instead of securing the pin 103 in a threaded socket in the member 102, the said pin may be adjustable toward and from the axis of said member as 75 shown in Figs. 6, 7 and 8. In this case, the pin 103 has a tapered threaded portion which extends into an eccentric aperture 106 formed eccentrically with a spring disk 107 set in the eccentric aperture 108 in the member 102. When the pin 103 is driven tightly into place, it spreads the spring disk 107 so as to lock it in its socket in any position to which it may be adjusted. 80 Referring again to Figs. 1 and 2, it will be 85 seen that the member 102 bears against the outer bushing 96. A spring 110 is placed upon said armature shaft so that the member 102 is held tightly against the said bushing so as to prevent the escape of water past 90 the parts to the motor. The armature, as illustrated, is of the tri-polar type, and is provided with the usual windings or coils which are connected with the commutator sections 111, as shown in Fig. 4. These sections 95 are secured to the face of a disk 112 on the armature shaft as shown in Fig. 2. The brush-supporting member 97 has about its hub 99, a ring 113 of insulating material through which carbon or other brushes 114 100 extend to engage the commutator sections 111, as shown in Figs. 4 and 5. Against each brush bears a spring 115 secured by a screw 116 to the outer face of the insulating ring 113. The two conductors of the cable 105 are respectively connected to the two springs 115. 110 By arranging the field magnet, of which the exterior is cylindrical with its poles extending away from the blade holder, I am able to locate the armature, the commutator and the brushes relatively remote from the holder. When the cap of the handle is removed, it exposes the brush holder, so that the binding posts, which attach the conductors to the brush springs, may be reached with a suitable instrument. And by removing the screws 94 94 and unscrewing the eccentric member 102, the whole motor, including the armature shaft, may be removed 115 120 for inspection or repair. The packing or gasket 93 prevents water from passing into the handle between the magnet and the handle, and between the sleeve 95 and the magnet; and the character of the two bushings 125 96 96 is such that water cannot pass between them and the armature shaft. Hence with the motor having its field magnet, its armature and commutator arranged as described, and with the means for rendering the handle 130

watertight (at the holder end), the blade and holder may be held under a running stream of water or immersed in a basin of water without danger of injury to the motor or short circuiting the current.

It is evident that the invention is not limited to the details of construction and arrangement which I have illustrated and described. For instance, the particular means for mounting and holding the blade, though simple and convenient may be changed, so that the invention may be embodied in safety razors of other kinds or having other forms of holding means. Again field magnets of other kinds may be used for the motor, and other details of the motor may be varied, though the form shown is the best, for general purposes, now known to me.

Having thus explained the nature of my said invention and described a way of constructing and using the same, although without attempting to set forth all of the forms in which it may be made, or all of the modes of its use, I declare that what I claim is:

1. A safety razor comprising a tubular casing which constitutes a handle, a head or holder affixed to the end of the casing at right angles thereto, said head or holder having a guideway, a smooth-edged razor blade arranged in the guideway, an electric motor concealed within said casing and having a rotary armature shaft extending longitudinally within said handle, and a crank on the end of said armature shaft engaging said blade to reciprocate it.

2. A safety razor comprising a tubular casing which constitutes a handle, an electric motor concealed within said handle and having a rotary armature shaft, means for closing the end of said casing to the passage of water, a head or holder on the said end of said handle, a reciprocatory smooth edged razor blade supported by said head or handle, and means for transmitting power from the end of said armature shaft to said blade.

3. A safety razor comprising a tubular casing which constitutes a handle having a threaded end, a head or holder secured to the threaded end of the handle, said head comprising a threaded member engaging the said threaded end, and members forming a guideway between them, a razor blade in said guideway, an electric motor in said handle having a rotary armature shaft, and a crank on the end of said shaft for reciprocating said blade.

4. A safety razor comprising a tubular casing which constitutes a handle, an electric motor concealed within said casing and having a rotary armature shaft, means in said handle encircling said armature shaft for preventing the entrance of water into said handle, a head or holder closing the end of said handle and arranged substantially at right angles thereto, a reciprocatory blade

supported by said head, and a crank pin carried by the armature shaft and engaging a slot in said blade.

5. A safety razor comprising a handle, a blade guide secured to said handle, a blade having a smooth cutting edge mounted reciprocatively in said guide and provided with a slot between its ends transverse to the direction of its edge and in the same plane with the edge, an electric motor contained in said handle, having a rotary armature shaft, and a crank carried by said shaft extending into said blade guide and contained in said slot; the blade being located in a plane approximately at right angles to the shaft, whereby the latter is enabled to reciprocate the blade by direct engagement.

6. A safety razor comprising a rotary electric motor, consisting of field poles, a rotary armature, an armature shaft, a commutator and brushes, in combination with a hollow handle inclosing and concealing said motor, a holder on the end of said handle, a smooth-edged reciprocatory blade on said holder connected to said armature shaft so as to be reciprocated thereby, and means at said end of the handle for closing it to the entrance of water.

7. A safety razor comprising a handle, a holder closing the end of said handle, a smooth-edged reciprocatory blade on said holder, an electric motor concealed in said handle and having a rotary armature shaft arranged perpendicularly to the face of said blade, and a crank pin on said shaft in direct engagement with said blade and with only the blade for reciprocating said blade.

8. A safety razor comprising a holder; a blade mounted to reciprocate thereon longitudinally of its cutting edge; a handle affixed to said holder at right angles thereto; an armature shaft journaled within said handle perpendicularly to said blade and having a power transmitting connection with said blade; a field magnet in said handle having its poles extending away from said blade, an armature on said shaft in the field of said magnet; a commutator on said shaft; and means at the holder end of said handle for preventing the access of water to said motor.

9. A safety razor comprising a holder; a blade mounted to reciprocate thereon longitudinally of its cutting edge; a handle affixed to said holder; an electric motor in said handle including an armature shaft, and an eccentric member in said holder affixed to said armature shaft and engaging a slot in the blade, said holder including a separable cover plate at the side of the blade away from the handle.

10. A safety razor comprising a reciprocatory blade; a holder having guides for said blade, said holder consisting of a base plate, a cover, and a hollow member on the

under side of said base plate; an eccentric member in said hollow member engaging a slot in the blade to effect its reciprocation in lines longitudinal of its cutting edge; a handle affixed to said hollow member, and a motor in said handle for rotating said eccentric member.

- 5 11. A safety razor comprising a holder having guard teeth, a smooth-edged blade 10 mounted thereon to reciprocate longitudinally of its edge, and having such edge between the guard teeth and the surface on which it is adapted to operate, a hollow handle affixed to said holder perpendicularly to 15 the plane of said blade and holder, and on the same side of the blade as the guard teeth, and a motor in said handle having a rotary armature shaft engaged with the blade for reciprocating the same.
- 20 12. A safety razor comprising a holder, a smooth-edged blade mounted thereon to reciprocate longitudinally of its edge, a hollow handle connected by a threaded joint with 25 said holder, a rotary shaft extending from the handle into operative relation to the blade, and having means thereon for reciprocating said blade, a motor in said handle for rotating said shaft, and means for 30 adjusting said blade transversely of its edge relatively to said shaft.

35 13. A safety razor comprising a closed tubular handle, a holder closing one end of said handle, means for sealing said end against the entrance of water, a cap closing the other end of said handle, a smooth-edged blade on said holder reciprocatory in lines longitudinal of its edge, and an electric motor confined within said handle for reciprocating said blade, all so arranged that the 40 holder end of the razor may be immersed to remove lather from the blade without admitting water to the motor.

- 45 14. A safety razor comprising a handle, a holder mounted on said handle, having a smooth surface bearing terminating in a straight and thin edge, a blade mounted reciprocatively on said holder to travel in a line approximately parallel to the edge of the holder, and having a straight smooth 50 edge parallel to its line of reciprocation projecting sufficiently far beyond the edge of the holder for the desired purpose, a rotary motor contained in said handle, and means for causing said motor to reciprocate said blade.

55 15. A safety razor comprising a handle, a holder mounted on said handle, having a smooth surface bearing terminating in a straight and thin edge, a blade mounted reciprocatively on said holder to travel in a line approximately parallel to the edge of the holder, and having a straight smooth edge parallel to its line of reciprocation projecting sufficiently far beyond the edge of 60 the holder for the desired purpose, an elec-

tric motor contained in said handle and having a rotary armature shaft, and a crank pin on said shaft projecting into direct engagement with said blade for reciprocating the blade.

70

16. A safety razor comprising a handle, a holder closing the end of said handle, a smooth-edged reciprocatory blade carried by said holder, said blade having a slot or notch extending transversely of its edge, an electric motor concealed in said handle and having a rotary armature shaft extending toward, and being substantially perpendicular to said blade, and a crank pin on said shaft extending into said slot or notch for engaging the bounding edges thereof, and thereby reciprocating the blade.

75

17. In a safety razor, a blade holder, a smooth-edged blade carried by said holder and adapted to reciprocate therein, means for reciprocating said blade with respect to said holder, complemental guide elements on said holder and blade independent of said reciprocating means for defining the path of the blade, one of said guides being adjustable to shift the position of the blade, and means for adjusting the same.

80

18. In a safety razor, a blade holder, a smooth-edged blade carried by said holder and adapted to reciprocate therein, means for imparting reciprocative movements to said blade, complemental guide elements on said holder and blade for defining the path of the latter, said holder-carried guide being adjustable to project the edge of said blade more or less, and means for adjusting the same.

85

19. In a safety razor, a blade-holder, a reciprocatory smooth-edged blade carried by said holder, means associated with said holder for reciprocating said blade, a guide on said holder for confining the reciprocations of the blade in a definite path, said guide being adjustable toward and from the edge of the holder, and means for adjusting the same.

90

20. In a safety razor, a blade-holder, a reciprocatory smooth-edged blade carried by said holder, means associated with said holder for reciprocating said blade, guide pins mounted on said holder for defining the path of the blade and adjustable toward and from the edge of the holder to vary the amount of projection of the blade, and means for so adjusting said pins.

100

21. In a safety razor, a holder provided with a guard plate, eccentrics pivoted to the holder and provided with guide pins, a reciprocating blade coöperating with said guide pins, whereby the eccentrics may be adjusted for shifting the guide pins and the blade with relation to an edge of the guard plate, and means for imparting reciprocating motion to the blade relative to the guard plate.

105

22. In a safety razor, a blade-holder having members adapted to embrace the opposite surfaces of a blade and form a runway for such blade, one of such members being 5 a guard, a reciprocatory blade having a straight cutting edge held in said runway, a handle fixed to one of said members having internal bearings, and a shaft rotatably mounted in said handle having a crank 10 pin for reciprocating said blade in directions parallel with its cutting edge, the runway being enlarged on both sides of the blade within the mouth thereof to provide a clearance space.
- 15 23. In a safety razor, a blade-holder comprising plates one of which is a guard to prevent cutting the skin of the user, adapted to embrace a blade between them at their edges, having plane bearing on the opposite 20 faces of the blade near the cutting edge thereof, and being cut away back of their edges on both sides of the blade to provide clearance spaces, one of the plates having a straight edge, in combination with a reciprocating blade having a straight cutting edge parallel to such plate edge, guiding 25 means engaged with said blade back of its cutting edge to retain the blade between said plates, and means for reciprocating said 30 blade.
24. In a safety razor, the combination of a blade-holder and a blade of substantially uniform thickness mounted to reciprocate in said holder in directions parallel with its 35 cutting edge, the holder consisting of members one of which is adapted to bear on the surface acted upon and has an edge parallel to and back of the edge of the blade, arranged to bear on the adjacent surface of 40 the blade with a plane bearing near the cutting edge thereof and being abruptly cleared away from the blade back of such edge.
25. In a safety razor, the combination of a blade-holder and a blade mounted to reciprocate in said holder, the holder being 45 constructed with means for guiding the blade and with provisions on both sides of the blade for permitting the blade to free itself of bits of hair which may work into the blade guideway. 50
26. In a safety razor, the combination of a blade-holder, a blade mounted to reciprocate in said holder, and formed with a slot between its ends perpendicular to its cutting edge, the holder consisting of plates 55 forming plane bearings for the opposite surfaces of said blade adjacent the cutting edge of the latter, and being recessed back of their bearing portions to free the blade, one of such plates having an edge parallel to 60 and back of the edge of the blade, and being arranged to bear against the surface acted on, when in use, a tubular handle secured to the other of said plates, an electric motor having a rotatable armature shaft in said 65 handle, and an eccentric pin on the end of the shaft projecting into the slot in the blade for reciprocating the latter.
27. A safety razor comprising a handle, a blade-holder comprising two plates, one 70 of which is rigidly secured to the handle and the other of which is hinged to the first, said plates having a space between them to receive a blade, and clamping members pivoted to the ends of one of said plates, each 75 said member having a fin arranged to enter an aperture in the adjacent end of the other plate.

In testimony whereof I have affixed my signature, in presence of two witnesses.
